MOLD

Robert L. Watson, McKeesport, Pa.

Application June 5, 1942, Serial No. 445,907

3 Claims. (Cl. 22—142)

This invention relates to improvements in apparatus for the molding and casting of articles such as billets, ingots, blooms, bars or other articles.

The primary object of this invention is the provision of molding apparatus primarily adapted for the molding of billets which will enable the casting of a plurality of readily separable billets efficiently and economically without any unnecessary waste of the molding material.

A further object of this invention is the provision of a mold apparatus for the molding of billets or ingots in which the molding space is so efficiently arranged as to eliminate the waste of the molding material.

A further object of this invention is the provision of a mold made up of a plurality of pieces which can be readily assembled or disassembled, the parts of which are such as to be readily replaceable so that should any part become damaged, it will not be necessary to replace the entire mold.

A further object of this invention is the provision of a knockdown mold comprising a plurality of walls which are relatively connected together so that they can be efficiently separated to expose the entire molded article or articles.

Other objects and advantages of this invention will be apparent during the course of the following detailed description.

In the accompanying drawings, forming a part of this specification, and wherein similar reference characters designate corresponding parts throughout the several views,

Figure 1 is a side elevation of the assembled mold.

Figure 2 is a vertical cross sectional view taken thru the mold.

Figure 3 is a horizontal cross sectional view taken thru the mold.

Figure 4 is a fragmentary top side elevational view of the molded contents showing the arrangement of the billets with respect to each other.

Figure 5 is a horizontal sectional view taken thru the connected billets as molded in the apparatus.

Figure 6 is a perspective view of the arrangement of the molded billets.

Figure 7 is a perspective view of one of the side walls of the mold.

Figure 8 is an inside surface view, in perspective, of the top plate of the mold.

In the drawings, wherein for the purpose of illustration is shown only a preferred embodiment of the invention, the letter A may generally designate the improved mold. It consists of side walls B, C, D and E; a bottom wall F and a top wall G.

The object molded by the improved apparatus is shown at H and consists of a plurality of billets, ingots, blooms, bars or other articles 10, 11, 12, 13 and 14 connected together and readily separable from each other.

10 The walls B, C, D and E are complementary and preferably of identical construction. The same includes a flat body portion 20 of general rectangular formation. Projecting in right angled relation from the inner surface 21 thereof is a separator rib or partition 22 which is preferably of the same thickness as one of the billets 10, 11, 12, 13 or 14. It is disposed in axial relation upon the body portion 20.

The walls B, C, D and E are so connected at 20 their side margins as to be interfitting, in a relation which will permit of their securement together in an exact relationship. Thus, each wall is provided with side marginal beveled edges 23 and 24 for a portion of the thickness thereof.

25 One side margin for the rest of the thickness has a surface 25 in right angled relation with the inner surface 21 and intersecting the same. The other side margin of the body 20 is offset at 26 to provide a step seat for the inner corner of 30 the adjacent wall. The interfitting of the side walls or plates in this relationship is shown best in Figure 3 of the drawings.

This seat 26 is provided along one side margin of each side plate. If desired, the side margins may be formed otherwise than herein described, since the purpose of forming these side edges thus is to facilitate exact seating and right angled positioning of the complementary side plates or walls in their assembled relation.

40 The bottom wall F includes a base portion 30 and upstanding corner flanges 31 at each corner and along each side thereof to provide movement limiting means for the interfitting of the side plates B, C, D and E thereagainst.

45 The top wall G is generally formed the same as the bottom wall. It has a top wall body 40 with corner flanges 41 along each side thereof to provide sockets for receiving the corner portions of the complementary assembled plates B, C, D and E in the relationship shown in the drawings. The top plate G is formed different from the bottom plate F in respect to a centrally disposed rectangularly-shaped pouring opening 50, which opens above the space 60 provided by the 55 facing surfaces 61 of the partitions 22. This

opening 50 may be as shown in the drawings or formed otherwise. Preferably, the opening 50 has communicating grooves 52 diagonally radiating from the corners thereof and extending over the billet forming cavities 65, 66, 67 and 68 formed at the junctures of the side plates of the mold; these grooves facilitating not only the pouring of the material in the mold but the complete filling of the mold cavities without air pockets, etc.

The arrangement of the billet cavities 60, 65, 66, 67 and 68 is shown in Figure 3 of the drawings. All of these cavities are of the same cross sectional area and the four corner cavities 65-68 are of the same height. The cavity 60 is increased in height by reason of the filler opening 50 so that the central billet portion is slightly higher than the corner billets 10-13.

The side wall partitions 22 are rounded at their inner corners to define very shallow passageways 70 between the central billet cavity 60 and each of the corner cavities 65-68. These small passageways form diagonally disposed connecting webs 80 which connect the corner billets 10-13 with the central billet 14, as is best shown in Figure 5 of the drawings. These webs 80 are so slender as to permit of relatively easy fracture thereof, and thus separation of the billets from each other.

As shown in the drawings, the molding apparatus is capable of producing five billets of substantially uniform size.

Means is provided to hold the walls B, C, D and E in their complementary assembled relation. This means may consist of angle brackets 90 and 91 welded along the outer side surfaces of each of the wall plates. In assembled relation the angle plates 90 and 91 of adjacent mold plates cooperate to receive adjusting bolt means 92 of any approved nature. In this manner the plates may be efficiently laterally clamped together.

The top and bottom plates are provided with means for clamping the same together upon the top and bottom edges of the mold. This means may consist of hooks 95 and 96 welded to the bottom and top plates respectively of the mold apparatus, at opposite sides of the mold apparatus. Rods 97 and 98 may be detachably connected upon these hooks and adjustably secured together by means of a turnbuckle arrangement 99 so that the top and bottom plates may be clamped securely in place upon the side walls or plates of the mold, as shown in Figures 1 and 2 of the drawings.

In Figures 4 and 6 it is noted that the billet

14 is provided with a top extension 14a and that the grooves 52 in the top wall of the mold form shallow webs 100 extending over the tops of the billets 10-13 inclusive. They are, of course, readily knocked out of position, but assist in maintaining the billets assembled until their severing is desirable.

Various changes in the shape, size and arrangement of parts of the improved mold and in the arrangement of the billets formed thereby may be made to the invention as herein shown and described, without departing from the spirit of the invention or the scope of the claims.

I claim:

1. Apparatus for the molding of billets and the like comprising a plurality of side plates, detachable top and bottom plates, means to detachably connect all of said plates together to form a chamber, and means in the chamber partitioning the same into a plurality of billet forming cavities consisting of a central billet cavity and corner billet cavities relatively separated from each other, all of said cavities having intercommunication along the vertical disposed adjacent edges thereof.

2. As an article of manufacture a mold comprising side walls, a top wall, a bottom wall, said side walls having spaced partitions rigid therewith intermediate the side margins thereof and

30 projecting into the chamber of the mold, said spaced partitions having their inner surfaces facing together in spaced relation to provide a mold cavity, each of the partitions being spaced at each of their side surfaces from the adjacent inside surfaces of the facing side walls to define mold cavities, the partitions being relatively spaced from each other at their most adjacent points to define passageways intercommunicating the mold cavities last mentioned with the first mentioned mold cavity whereby metal poured into the first mentioned mold cavity will flow uniformly into the other mold cavities and fill the same at the same time that the first mentioned cavity is being filled.

45 3. In a folded arrangement of billets, ingots, blooms or like molded articles, the combination of a central billet and a plurality of billets surrounding the same and connected therewith by relatively thin frangible webs, the central billet being relatively higher and extending above the top surfaces of the other billets and being connected at said extension with the top surfaces of the said other billets by means of fracturable web flanges.

55 ROBERT L. WATSON.
